UNITED STATES PATENT OFFICE.

PIERRE ZUCCO, OF SAN FRANCISCO, CALIFORNIA.

APPARATUS FOR AND METHOD OF BUILDING CONSTRUCTION.

Application filed February 5, 1925. Serial No. 6,927.

This invention relates particularly to a method of building construction.

An object of the invention is to provide a rapid and economical process for constructing 5 reinforced concrete floors formed integrally with concrete T beams.

A further object of the invention is to provide collapsible forms adapted to be connected together in operative position on a 10 false work ceiling and a suitable monolithic mass poured into the forms and between the forms to form an integral ceiling and T beams, the said forms being so arranged that after the monolithic mass has hardened, they 15 may be removed.

A still further object of the invention is to provide adjustable clamps for holding the forms of rows of concrete molds together to permit adjusting movement of the rows 20 of forms relative to each other.

In this specification and the annexed drawings, the invention is illustrated in the form considered to be the best, but it is to be understood that the invention is not limited 25 to such form, because it may be embodied in other forms, and it is also to be understood that in and by the claims following the description, it is desired to cover the invention in whatsoever form it may be 30 embodied.

In the accompanying one sheet of drawings—

Fig. 1 represents an isometric view of the form for securing T beams in accordance 35 with my invention.

Fig. 2 is an isometric view showing a pair of parallel T beam forms, resting on a false work ceiling preparatory to the pouring of the concrete therein.

Fig. 3 is an isometric view of the hardened concrete mass after the forms have been removed therefrom.

Fig. 4 is an isometric view showing a mode of completing a hollow form in accordance 45 with the present invention, with a wooden flooring applied thereon.

Fig. 5 is a view of a hollow floor built in accordance with my invention, finished with slabs between the tops of the cast and forms, 50 and a plastic finish on top of all to make a uniform floor.

The metal forms, used in accordance with my invention, consist of complementary

right and left plates 1, bent so that one end of each plate will lie at an angle to the 55 opposite end of the same plate. The plates 1 are preferably arranged side by side in parallel rows and the horizontal ends of right and left plates of different rows clamped together by means of clamping bars 60 2 and 3, engaging the plate ends on the upper and lower faces thereof. The clamp bars 2 and 3 are held together by means of a slotted bolt 4, having a wedge pin 5 extending therethrough, for the purpose of drawing the plates 2 and 3 together, and hence rigidly clamping the ends of the plates 1. The wedge tightener 5 is a simple form of device for drawing the clamping bars 2 and 3 together, although it would be clearly 65 within the purview of the invention to utilize any equivalent form of tightening apparatus.

The right and left plates in adjacent rows are spaced relative to each other by tightening or loosening the wedge pin 5 on the clamp bars 2 and 3. Thus the right and left halves of adjacent forms may be joined together in advance of the actual use thereof. The plates 1 are shaped as forms in which 75 the T beams to carry the loads are molded. The strength of the beams is calculated to carry the loads necessary, but the size of the said beams can be easily modified by regulating the clamping bars 2 and 3 to increase 80 or diminish the space between the opposite halves of the same form. The clamping bar arrangement also permits the equal spacing of a number of the T beam forms over 85 a prescribed area by spreading apart, or drawing together the beam forms, thus increasing or diminishing the space between rows of beam forms. The ends of the top clamp bar 3 are bent at right angles upwardly, to serve as a support for the wood strips 90 95 11, to be hereinafter described in detail.

For the construction of a ceiling and beams in accordance with my invention, I first provide a false work ceiling 6, on which I place a metallic screening 8 which will 100 serve to reinforce concrete poured thereon. In order to pour the concrete into the ceiling and beams in a single operation, I place a plurality of metal supports or chairs 7 on the ceiling 6. The ends of the supports 7 105 are of a width which corresponds to the

breadth of the base of the beams to be formed. The form plates 1 are rested in a vertical position on the supports 7, the said supports spacing the bottom edges of the form plates 1 away from the false work ceiling a distance corresponding to the depth or thickness of the concrete ceiling to be formed. Each T beam form consists of a right and left plate 1, spaced apart a predetermined distance on the supports 7. The T beam forms are arranged in rows and the horizontal ends of right and left forms of adjacent beam rows are connected together by the clamping bars 2 and 3. In order to reinforce the beams a pair of reinforcing bars 9 are arranged in spaced relation on the screening 8 within the form plates 1 and are bound together by means of the steel wires 10, the ends of which are bent parallel to the vertical plane of the bars 9, giving to the bars 9 and wires 10 a T form substantially the same as that of the beams to be molded. After the various rows of beam forms have been connected together, and arranged in the manner set forth, a plastic mixture of concrete would be poured through the clamping bars 2 and 3 connecting the horizontal right and left halves of adjacent parallel forms, to form a concrete layer of predetermined thickness. Directly after the layer of concrete is poured into the space between the beam forms, the concrete would be poured into the beam forms and in and around the reinforcing therein. The concrete would be prevented from escaping outwardly at the bottom of the sides of the forms on account of the space therein existing having previously been filled by the first poured mixture of concrete. In order to fill the beam forms with concrete to any desired height I place wooden joists 11, of the height required, along the horizontal right and left halves of each form plate resting said joists against the bent ends of the upper clamp bar 3. After the poured concrete has hardened sufficiently the clamp bars 2 and 3 would be unloosened, permitting the right and left form plates 1 to be lifted away from each concrete beam and withdrawn therefrom outwardly through the space between the parallel concrete beams. The plates may then be re-assembled and used for future molding operations. The metallic supports 7 on which the form plates 1 rest, preliminarily to pouring, remain embedded in the concrete after it has set. In order to form a flooring on the concrete beams, I enclose the space between the horizontal faces of the rows of concrete beams by pre-cast concrete slabs 14, after which the upper edges of the beams and the interposed slabs would be covered with plastic material 15 to form a floor finish. If a wood floor is desired the wood joists 11 would be attached integrally to the concrete forms during the

pouring operation, so that after the beams have hardened the joists would be rigidly secured thereto. A covering of insulating felt 12 is placed over the upper faces of the concrete beams and over said felt the floor 13 is laid. It is to be noticed that the hollow space between the T beams constitutes an air cushion which forms an insulator for heat in summer and the cold in winter, and at the same time furnishes an adequate non-conductor of sounds. The free spaces between the various beams can be utilized for concealing pipes 16 or for carrying electric wire conduits or said spaces can be filled with insulating material to decrease the conductivity of sounds and heat in the said building.

Having thus described this invention, what I claim and desire to secure by Letters Patent is:—

1. A method of building construction comprising, forming a temporary planar surface; arranging rows of beam forms in spaced relation to said surface; connecting the contiguous sides of the opposite rows of beam forms; filling the beam forms and the space between the beam forms and said surface with plastic concrete; and removing the supporting surface and beam forms after the concrete in the forms and between the forms has hardened.

2. A method of building construction comprising, forming a temporary planar surface; arranging rows of beam forms in spaced relation to said surface; connecting the contiguous sides of the opposite rows of beam forms; filling the beam forms and the space between the beam forms and said surface with plastic concrete; allowing the concrete to harden; removing the forms from the concrete; and covering the upper surface of the concrete beams with flooring material.

3. An apparatus for forming concrete beams, comprising a plurality of rows of complementary plates shaped to form beams of the desired contour; adjustable clamps connecting the adjacent plates of opposite beam rows, to permit the connected plates to be moved relatively toward or from each other; and means to hold down opposite ends of the plates in spaced relation.

4. An apparatus for forming concrete beams comprising, plural rows of oppositely flanged form members; adjustable clamping bars connecting the oppositely flanged form members of adjacent beam rows; and means independent of the form members connecting the oppositely flanged form members of the same beam rows to regulate the width of the beams to be formed and to allow the joinder of the concrete between the beams.

5. An apparatus for forming concrete beams, comprising a plurality of rows of

complementary plates shaped to form beams of the desired contour; adjustable clamps connecting the adjacent plates of opposite beam rows, to permit the connected plates to be moved relatively toward or from each other; and means independent of the form members connecting the complementary

plates of the same beam rows to regulate the width of the beams to be formed.

In testimony whereof, I have hereunto set my hand at San Francisco, California, this 21st day of January 1925.

PIERRE ZUCCO.
